UNITED STATES PATENT OFFICE.

WALDEMAR DYRSSEN, OF NEW YORK, N. Y.

ТИЛТИНГ ФУРНАС.

1,416,699.

Specification of Letters Patent. Patented May 23, 1922.

Application filed December 2, 1920. Serial No. 427,778.

To all whom it may concern:

Be it known that I, WALDEMAR DYRSSEN, a subject of the King of Sweden, and resident of the city, county, and State of New York, have invented certain new and useful Improvements in Tilting Furnaces, of which the following is a specification.

My invention aims to provide certain improvements in the mechanism for controlling the tilting movement of furnaces by which the power required for the tilting operation is comparatively low, and whereby other advantages may be secured as herein-after described.

15 The accompanying drawings illustrate a furnace embodying the invention.

Fig. 1 is a side elevation and Fig. 2 a partial cross-section on the line 2—2 of Fig. 1.

The furnace 1 is an electric tilting furnace, the invention being particularly designed for this class of apparatus. It has electrodes 2 passing down through the roof, each carried by a holder 3 with an arm 4 supported on a post 5 guided on the side of 20 the furnace and operated by motors mounted also on the rear side of the furnace. The mechanism for supporting and adjusting the electrodes may be of any usual or suitable type and is not illustrated in detail, the particular arrangement indicated being covered 25 in detail in an application of James H. Gray No. 423,867 filed November 13, 1920 and pending concurrently herewith.

The furnace has a spout 6 for pouring 30 the molten metal, when the furnace is tilted, into a ladle 7. On the bottom of the furnace are mounted rockers 8, usually two in number, the lower faces of which bear on tracks 9 supported on the foundation 10. Each of 35 the rockers is connected near its rear end with a link 10^a mounted on a crank pin on a gear 11 which is driven by separate intermediate gearing from a motor 12. As the gear 11 is rotated the furnace is tilted to its 40 pouring position and back to its upright or working position. Each of the rockers 8 is provided at one side with a toothed portion 13, Fig. 2, engaging a similar toothed portion 14 on the corresponding track member 9. The center of rotation of the furnace is 45 indicated at 15. The toothed engagement of the rockers with their tracks prevents any slipping between these parts or any turning

of the furnace sidewise during the tilting movement.

55 The bearing faces of the rockers and tracks respectively are so shaped that as the furnace is tilted its center of rotation 15 will move forward and along a substantially or approximately horizontal line 16 to the 60 position shown in dotted lines. Various curvatures may be given to the opposed bearing faces of the rockers and tracks in order to secure this result. Preferably a convex curvature is given to each of the 65 opposed bearing faces. Were either of the opposed bearing faces made flatter, the other face would have to be more sharply curved to secure the same movement of the center. By making them of approximately equal 70 convex curvature the space occupied by them in a vertical direction is reduced to a minimum, and this is advantageous particularly in the case of large furnaces. Headroom is saved, weight is reduced and the actual cost 75 of the rockers is reduced to about half.

The moving of the furnace forward as it is tilted to the pouring position avoids having to place the ladle close against the furnace, as it has been necessary particularly 80 where furnaces have been pivoted at a fixed point. The movement along a substantially horizontal line requires a minimum of power for the tilting operation.

85 The bearing faces may be such as to give an exactly horizontal movement to the center of gravity of the furnace. Preferably, however, for the sake of safety I design the bearing faces so that the center of gravity will be below the center of rotation and 90 will be given a slight lift in moving from the upright to the tilted position, just sufficient to cause the furnace to return to its upright position in case of breakage of the 95 tilting gearing, or similar accident.

In determining the curvatures of the rockers and tracks I first find the center of gravity of the furnace and select a point a few inches (say six to twelve inches) above it as my center of rotation; that is, the point 100 which I desire to move in a practically horizontal line in tilting. The radius of the rockers and tracks can then be selected to produce this practically horizontal movement. If the two arcs be circular and of 105 equal radii and if the center of rotation 15

is located half way between the face of the rocker and its center, it will have a substantially straight horizontal movement throughout the distance necessary to tilt the furnace.

- Though I have described with great particularity of detail a certain embodiment of my invention, yet it is not to be understood therefrom that the invention is restricted to 10 the embodiment disclosed. Various modifications thereof in detail and in the arrangement of the parts may be made by those skilled in the art without departure from the invention as defined in the following claims.

What I claim is:

1. A tilting furnace provided with rockers

rolling on curved tracks, the bearing faces being shaped to produce an approximately horizontal movement of the center of gravity of the furnace. 20

2. A tilting furnace provided with rockers rolling on tracks, the bearing faces of the rockers and tracks respectively being convexly curved and of approximately equal 25 curvature.

3. A tilting furnace in combination with means for moving it forward on an approximately horizontal line as it is tilted and slightly elevating its center of gravity in 30 the tilted position.

In witness whereof, I have hereunto signed my name.

WALDEMAR DYRSSEN.
